Inventor:
George E. Young,
by Alexander S. Lam
His Attorney.

UNITED STATES PATENT OFFICE.

GEORGE E. YOUNG, OF SCHENECTADY, NEW YORK, ASSIGNOR TO GENERAL ELECTRIC COMPANY, A CORPORATION OF NEW YORK.

SEARCHLIGHT.

Application filed January 19, 1923. Serial No. 613,588.

To all whom it may concern:

Be it known that I, GEORGE E. YOUNG, a citizen of the United States, residing at Schenectady, in the county of Schenectady, State of New York, have invented certain new and useful Improvements in Searchlights, of which the following is a specification.

My invention relates to searchlights and also to incandescent lamp mountings and has among its objects the following:

To provide means whereby incandescent lamps of high wattage may be used in connection with tilting projectors and to insure a constant position of the incandescent lamp while the tilting takes place.

To provide means for mounting the incandescent lamp in an upright position whereby a projector associated therewith may be moved from one position to another without disturbing the lamp; and

To form a pendulum-like structure of the light source and its support.

To accomplish the foregoing, means are provided such as hereinafter set forth and claimed, reference being had to the accompanying drawing.

In the drawing which accompanies this specification;

Fig. 1 is a side view, partly in section of the searchlight, the section being taken on line 1—1, of Fig. 2 and

Fig. 2 is a front view in section of the searchlight and of the incandescent lamp mounting, the section being taken on line 2—2, of Fig. 1.

Referring more in detail to the drawing, the incandescent lamp 2 is shown associated with a searchlight of the usual type which is provided with the usual reflector 3, drum D, and window 5. As more clearly shown in Fig. 2, the incandescent lamp is shown mounted on a pivotal support A. This support comprises a pair of arms 4 and 5 which are mounted in suitable bearings 6 and 7, respectively. The arm 4 as shown terminates in an annular ring 8 while the arm 5 terminates in the annular ring 9. The bearings 6 and 7 are provided with pins which project toward the lamp and which extend through the rings 8 and 9. These pins and the bearings are hollow and through these hollow portions conductors 10 and 11 extend

which terminate in posts 12 and 13. These posts are attached to the plate 14. The terminals of the lamp, as will be seen, also engage the terminals 12 and 13. An electrical connection is therefore supplied by means of which current is conveyed to the lamp 2 for operating the latter. As shown, the arms 4 and 5 are strapped together by means of the plate 14 so as to form a more or less rigid structure which will swing as a whole about the bearings 6 and 7. All of the parts of the support A contribute toward producing a weight for maintaining the lamp 2 in its upright position as shown in Fig. 2. If desired the plate 14 may be made of heavier or thicker material, the object being to stabilize the lamp 2 in its upright position inasmuch as lamps of this character last longer if held in an upright position.

With a device constructed as above explained it is possible to use as a source of light in a searchlight a high power incandescent lamp inasmuch as the lamp may be maintained in an upright position while the projector may be moved so as to swing the beam without disturbing the position of the lamp.

Heretofore in certain types of lamps the reflector 3 has in some instances been pivoted but this is the first construction that enables the drum and reflector to be tilted so as to throw the beam up or down while the lamp remains stationary without throwing the lamp out of focus.

While I have shown my invention in a particular embodiment as required, I do not wish to be limited to any particular construction inasmuch as with the disclosure herein made variations in structure will readily suggest themselves to those skilled in the art. Such modifications will of course fall within the scope of my invention as covered by the claims contained herein.

What I claim as new and desire to secure by Letters Patent of the United States, is:

1. A light projector comprising in combination a reflector, a casing about said reflector, a frame supported within said casing to swing freely therein, and a source of light mounted on said frame to move together with said frame, said light and frame being mounted with respect to said reflector

so that the source of light is maintained substantially at the focal point of the reflector in every position of the frame when the frame is swung about its axis.

5 2. A light projector comprising in combination a reflector, a casing about the reflector, a frame supported to freely swing within said casing, and a source of light

secured to said frame to move therewith, said light and frame being mounted so that 10 the light source is maintained in a constant position when the axis of the casing is tilted.

In witness whereof, I have hereunto set my hand this 17th day of January, 1923.

GEORGE E. YOUNG.
